UNITED STATES PATENT OFFICE.

GEORGE AMBORN, OF NEW YORK, N. Y., ASSIGNOR TO J. H. WILLIAMS & CO., OF BROOKLYN,
NEW YORK, A CORPORATION OF NEW YORK.

CHAIN PIPE-WRENCH.

No. 876,926.

Specification of Letters Patent.

Patented Jan. 21, 1908.

Application filed May 6, 1907. Serial No. 372,037.

To all whom it may concern:

Be it known that I, GEORGE AMBORN, a citizen of the United States, residing in the borough of Brooklyn, county of Kings, city and State of New York, have invented certain new and useful Improvements in Chain Pipe-Wrenches, of which the following is a specification.

This invention relates to chain pipe wrenches or the like and aims to provide certain improvements therein.

The present invention relates particularly to that type of wrench in which laterally separated jaws are provided between which the chain is centrally pivoted so that it may swing to one side or the other and thus be adapted for operation in connection with either of the working faces of the jaws.

The principal object of the present invention is to provide a wrench of this type in which the jaws are double ended so that each is provided with two sets of working faces, such jaws being adapted to be reversed with relation to the handle so that one or the other set of working faces may be brought into operative position. In the preferred construction of my invention, the chain is pivoted in a fixed position centrally of the jaws, so that it is not necessary to detach it when the jaws are reversed. Preferably also I provide a single lock on each side of the wrench which is adapted to operate when the jaws are in either position relatively to the handle.

By my invention I am enabled to provide a reversible jawed wrench, the jaws of which are but little longer than in the ordinary fixed jawed constructions.

Referring to the drawings which illustrate several embodiments of my invention, Figure 1 is a side elevation of the wrench showing the preferred construction; Fig. 2 is a top or plan view; Fig. 3 is an elevation of the inner side of one of the jaws; Fig. 4 is a section on the line 4-4 in Fig. 1; Fig. 5 is a side elevation showing a modified construction; Fig. 6 is a section on the line 6-6 in Fig. 5.

Referring first to Figs. 1 to 4, let A indicate a suitable handle or shank which has fixed to its forward end two jaws B, B' as shown.

Each of the jaws B, B' is double ended, that is to say, instead of having only the working faces *a*, *a'* on its front end, these

faces are duplicated as shown at *b*, *b'* at its rear end. Preferably the faces *a* and *b* and *a'* and *b'* are connected respectively by a curved portion *c*, or *c'*, such portions in use serving as gages by which the necessary length of loop of the chain can be determined in a well known manner. In the present construction the portions *c*, *c'* are adapted for use either in the normal or reversed position of the jaws.

The jaws are preferably fixed to the handle by means of bolts *d* and *e*, the former of which passes through holes *f*, *f'* in the jaws and a hole *h* in the handle, and the latter of which passes through holes *g* in the jaws and *h* in the handle. Preferably the jaws are slotted to receive the sides of the handle. The bolt *e* also serves as a pivot pin for the eye *j* to which the chain is connected. It is important that the bolt *e* be centrally arranged, that is to say, that it shall be disposed in such a position that the chain C shall be capable of swinging to either the upper or under side of the wrench so as to bring the upper or lower working face *a* or *a'* into operation. This arrangement of the pivot pin of the chain is also important in that it enables the chain to act from the same point when the jaws are reversed, so that it is not necessary to alter the position of the pin or other connection. In the present construction, in order to reverse the jaws the bolt *d* is removed and the bolt *e* slackened sufficiently to permit the disengagement of the jaws from the handle whereupon they may be turned around the bolt *e* to their reverse positions in which the holes *j'* in the jaws are brought into coincidence with the hole *h* of the handle whereupon the bolt *d* is replaced and both bolts tightened.

An important feature of the present invention is the construction of locking means for the free end of the chain. In the preferred construction of the invention a single lock is provided on each side of the wrench midway between the ends thereof, such lock being adapted to engage the chain in both positions of the jaws. The form of the lock depends more or less upon the type of chain which is used. I have illustrated in Fig. 1 a chain composed of flat links having their pivot pins extended laterally outward to form locking pintles, and in connection with this form of chain I prefer to employ the lock

illustrated in Fig. 3. This figure shows one side of the lock, this side being duplicated on the opposite jaw. As shown the lock comprises two hook-like members *m*, *n* which face in opposite directions. Each of such members has a recess *m'* or *n'* which is adapted to be engaged by a pintle of the chain. Each of the hooks is extended such a distance with relation to the opposite recess that when a pintle is engaged in either recess the next succeeding pintle can just pass over the opposite hook. In order to engage the chain with the lock, the desired pintle is brought rearwardly into the recess *n'* whereupon the next rearward pintle slips over the rear hook and the chain is then in position for use. It is to be noted that while the rear hook acts to hold the chain against the forward stress in use, the front hook acts as a retaining device therefor. This is an important feature since in many positions of use the chain tends to slip out of engagement with the lock. With the present construction of lock this is possible only when one of the pintles is in close engagement with the bottom or end of the locking recess, and even under these circumstances it is necessary that the adjacent pintle shall be moved laterally outward in order that the engaged 30 pintle may be then disengaged. These movements seldom if ever accidentally occur in practice. The opposite half of the lock formed upon the jaw B is of the same construction as that just described. It will be understood that this construction of lock is duplicated on the under side of the wrench.

In use the wrench is employed in the ordinary manner, the working face *a* or *a'* being brought into operation as convenient. 40 When these faces become worn or dull the jaws may be reversed and the working faces *b* and *b'* brought to the front.

In Figs. 5 and 6 I have illustrated my invention as applied to a wrench having a chain, the links of which are formed with side wings or lugs which are adapted to engage the locking means on the jaws or handle. Such lugs are indicated at *q*. With this construction of chain I prefer to construct the locks *r* as circular projections formed on the inner sides of the jaws, such projections being engaged at their rear by the lugs *q* on the chain. It will be noted in this construction as in that hereinbefore described that the same locks are adapted to operate in both the normal and the reverse positions of the jaws.

It will be seen that by my invention I provide a chain pipe wrench or analogous device 60 in which the wrench has double the wearing capacity of the single jawed wrenches now in use, and in which the jaws have but little greater length and weight than those having but two working faces. It will also be observed that I provide a construction in which

the chain is connected to the wrench at a single fixed point from which it is capable of operation in all positions of the jaws. This is especially important in the type of wrench shown wherein the chain is locked upon the opposite side to the pipe. It is also to be noted that by my invention I am able to provide a single lock which is capable of operation when the jaws are in either their normal or reverse positions. This is of considerable advantage in that it permits me to shorten the length of the jaws and to discard a lock on each side of the wrench. 75

It will be observed that I do not wish to be limited to the modifications of my invention herein shown as many changes may be made therein without departing from the invention.

It is to be understood that my invention is applicable to other devices than chain wrenches, such for instance, as chain pipe vises or the like.

What I claim is:

1. In a chain pipe wrench, the combination of a handle, a double ended reversible jaw connected therewith, a chain pivoted centrally of said jaw whereby such chain acts from the same point when the jaw is reversed, and locks formed upon the jaw for engaging such chain. 95

2. In a chain pipe wrench, the combination of a handle, a double ended reversible jaw connected therewith, a chain pivoted thereto, and a single lock fixed relatively to the jaw for engaging such chain in both positions of said jaw. 100

3. In a chain pipe wrench, the combination of a handle, a double ended reversible jaw connected therewith, a chain pivoted centrally of said jaw whereby such chain acts from the same point when the jaw is reversed, and a single lock fixed relatively to the jaw for engaging such chain in both positions of said jaw. 105

4. In a chain pipe wrench, the combination of a handle, a double ended reversible jaw connected therewith, a chain connected with such wrench, and a lock for engaging such chain in both positions of said jaw; said lock having two hook-like members each of which is adapted to act as a locking member in one position of the jaw and a retaining member in the other position of the jaw. 110

5. In a chain pipe wrench, the combination of a handle, a double ended reversible jaw connected therewith, a chain having pintles, and a lock engaging such pintles in both positions of the jaw, such lock having two hook-like members reversely arranged and two oppositely arranged recesses, such parts being proportioned so that when one of such pintles is in position at the bottom of one recess the next adjacent pintle can pass over the end of the opposite hook-like member. 120

6. In a chain pipe wrench, the combination of a handle, two double ended reversible jaws connected with said handle, one on each side thereof, a chain centrally pivoted between such jaws and adapted to swing to either side of such jaws, such jaws being adapted to be reversed to bring their opposite ends into operative position, and said chain adapted to coöperate with both of the ends of such jaws without changing its point of

connection, and locks formed upon the jaws for engaging said chain.

In witness whereof, I have hereunto signed my name in the presence of two subscribing witnesses.

GEORGE AMBORN.
